(57) **CLAIM**

The ornamental design for a TV stand, as shown and described.

DESCRIPTION

FIG. 1 is a perspective view of a first embodiment of a TV stand showing my new design;

FIG. 2 is a perspective view thereof with the movable shelf shown in a different position;

FIG. 3 is an enlarged partial view of the area indicated by line 3—3 in FIG. 1;

FIG. 4 is a front orthographic view of the first embodiment of the TV stand;

FIG. 5 is a top orthographic view thereof;

FIG. 6 is a right side orthographic view thereof;

FIG. 7 is a left side orthographic view thereof;

FIG. 8 is an enlarged partial view of the area indicated by line 8—8 in FIG. 6;

FIG. 9 is an enlarged partial view of the area indicated by line 9—9 in FIG. 6;

FIG. 10 is a perspective view of a second embodiment of a TV stand showing my new design;

FIG. 11 is a perspective view thereof with the movable shelf shown in a different position;

FIG. 12 is an enlarged partial view of the area indicated by line 12—12 in FIG. 10;

FIG. 13 is a front orthographic view of the second embodiment of the TV stand;

FIG. 14 is a top orthographic view thereof;

FIG. 15 is a right side orthographic view thereof;

FIG. 16 is a left side orthographic view thereof;

FIG. 17 an enlarged partial view of the area indicated by line 17—17 in FIG. 15;

FIG. 18 is an enlarged partial view of the area indicated by line 18—18 in FIG. 15;

FIG. 19 is a perspective view of a third embodiment of a TV stand showing my new design;

FIG. 20 is a perspective view thereof with the movable shelf shown in a different position;

FIG. 21 is an enlarged partial view of the area indicated by line 21—21 in FIG. 19;

FIG. 22 is a front orthographic view of the third embodiment of the TV stand;

FIG. 23 is a top orthographic view thereof;

FIG. 24 is a right side orthographic view thereof;

FIG. 25 is a left side orthographic view thereof;

FIG. 26 is an enlarged partial view of the area indicated by line 26—26 in FIG. 24;

FIG. 27 is an enlarged partial view of the area indicated by line 27—27 in FIG. 24;

FIG. 28 is a perspective view of a fourth embodiment of a TV stand showing my new design;

FIG. 29 is a perspective view thereof with the movable shelves shown in different positions;

FIG. 30 is an enlarged partial view of the area indicated by line 30—30 in FIG. 28;

FIG. 31 is a front orthographic view of the fourth embodiment of the TV stand;

FIG. 32 is a top orthographic view thereof;

FIG. 33 is a right side orthographic view thereof;

FIG. 34 is a left side orthographic view thereof;

FIG. 35 is an enlarged partial view of the area indicated by line 35—35 in FIG. 33; and,

FIG. 36 is an enlarged partial view of the area indicated by line 36—36 in FIG. 33.

The broken lines shown in FIGS. 1-36 are included for the purpose of illustrating environmental elements only and form no part of the claimed design.
